UNITED STATES PATENT OFFICE.

HENRY SOULIER, OF PROVO, UTAH.

DESIGN FOR A TOILET-CABINET.

49,628.

Specification for Design.

Patented Sept. 5, 1916.

Application filed June 13, 1916. Serial No. 103,584. Term of patent 14 years.

To all whom it may concern:

Be it known that I, HENRY SOULIER, a citizen of the United States, residing at Provo, in the county of Utah and State of Utah, have invented a new, original, and ornamental Design for Toilet-Cabinets, of which the following is a specification, reference being had to the accompanying drawing, forming a part thereof.

The figure is a perspective view of a toilet cabinet, showing my new design.

I claim:

The ornamental design for a toilet cabinet, as shown.

HENRY SOULIER.

Witnesses:

WILFORD S. GRAY,
J. N. PROUS.
